United States Patent Office.

JOHN A. WHIPPLE, OF CAMBRIDGE, MASSACHUSETTS.

Letters Patent No. 65,142, dated May 28, 1867.

COMBINED MATCH-BOX AND TAPER-HOLDER.

The Schedule referred to in these Letters Patent and making part of the same.

Be it known that I, JOHN A. WHIPPLE, of Cambridge, in the county of Middlesex, and State of Massachusetts, have invented a new and improved Combined Taper-Holder and Match-Box, of which the following is a full, clear, and exact description, reference being had to the accompanying drawings, making part of this specification, in which—

Figure 1 is a perspective view of the device when closed.

Figure 2 is a view of the same when opened; and

Figure 3 is longitudinal section of the same.

The object of my invention is to provide a convenient means for furnishing a light to be used on occasions where an ordinary lamp might not be easily accessible or convenient to carry about; and the invention consists of a folding case of a size convenient to be carried in the pocket, and provided with compartments for holding matches and a taper or candle, so that the latter may be readily lighted and carried about, or, with its holder, may be placed upon a support and answer the purpose of a lamp.

Referring to the drawings, A B in the several figures represent an oblong case formed of two compartments, and hinged together as shown. The part B is of a hollow cylindrical form, open at its outer end, and designed for containing matches. When closed it is made to fit partially within the part A, the end of the latter serving as a cover to prevent the matches from escaping from the part B. To the end of the portion B where it is hinged to the part A, is hinged a socket, S, for holding a candle or taper. The said socket S is so arranged as to fold within the part A, as shown in fig. 3, when the device is closed and the candle or taper not required for use. When the candle is to be used, the part B is opened so as to admit of the socket and taper being turned outward, when it will rest upon the portion A, and hold the taper or candle in an upright position, the case serving as a stand or holder for the same. The whole device may be made to occupy but a small space so as to be conveniently carried in the pocket. The socket hinge is to be so constructed as to prevent the socket from being turned over when in an upright position and in use. The sides may be of curved or other form, and the end of the case may be roughened to ignite the matches. The device may be made of metal or any other suitable material.

What I claim as my invention, and desire to secure by Letters Patent, is—

The combination of the casing A, the match-holder B, and hinged socket S, substantially as and for the purpose specified.

In testimony whereof I have signed my name to this specification in the presence of two subscribing witnesses.
